CUT.

FUSE-PLUG.

1,335,362.

Specification of Letters Patent. Patented Mar. 30, 1920.

Application filed March 20, 1916. Serial No. 85,250.

To all whom it may concern:

Be it known that we, TONJES A. C. BOTH, of Stratford, in the county of Fairfield and State of Connecticut, ALEXANDER H. TRUMBULL, of said Stratford, and RALPH A. SCHOENBERG, of New York, in the county and State of New York, have invented a new and useful Fuse-Plug, of which the following is a specification.

10 The chief objects of our invention are to improve the efficiency and construction of fuse plugs.

With these objects in view one feature of our invention consists in a pilot or lead on the shell at that end of the plug which enters the receptacle, this portion in the form shown being unthreaded and of substantially less diameter than the diameter of the threaded portion. One great advantage of this feature is that in starting the plug into its receptacle a lead is provided to hold the plug in position so as to thread it into the receptacle and the plug starts at once to screw into place whereas heretofore if the threads are not in alinement and the plug is tipped a little the plug will not screw into the receptacle. This is bad because as a rule the receptacles for fuses are somewhat inaccessible and difficult to reach to renew fuses 30 and on account of the position of the user the latter will easily tip the fuse plug so that it will not enter the receptacle or cutout readily. With our invention, however, it is practically impossible to tip the plug to such an extent as to prevent immediate threaded engagement on turning of the plug. Another great advantage of this feature of our fuse is that for a given size plug there are required less turns of the plug to put it fully 40 into the receptacle and this is of particularly important advantage in cases where the receptacles are somewhat inaccessible because the user will have less rotation to effect.

This pilot or lead feature is particularly 45 advantageous in fuse plugs in which the lining for the screw shell is of non-brittle material such as fiber but it is also highly useful in fuse plugs of other types.

Another feature of our invention consists 50 in a substantial and positive barrier located in the direct line between the center contact and the point of connection of the fuse wire and shell. In the preferred form this par-

tition extends crosswise of the plug. The object of this feature is to prevent the holding of an arc on blowing of the fuse which arc is likely to burn the shell and cause other damage. 55

Another feature of our invention is a background near the fuse wire so that one may easily tell whether or not the fuse has blown, it being a fact that when a fuse blows it usually blackens or chars the covering so that heretofore it has been difficult to see into the fuse plug sufficiently well to determine accurately whether the fuse has blown or not. In the preferred form the background is of a color contrasting with the color of the fuse wire. 65

Another feature of our invention is a partition which divides the interior of the fuse plug into two chambers so that when the blow out occurs the pressure of the gases is divided and the connection at each end of the fuse wire is protected against arcing or 70 burning. 75

Another feature of our invention is a vent arranged so that the escaping gases will not come in contact with any metal parts in passing out of the plug and thereby avoiding melting or burning of such parts and avoiding flame outside of the fuse plug. 80

Another feature of our invention is an outside washer which resembles a valve in its action. The purpose of this is to provide a damper to prevent the escape of gas in the form of a flame. Very slight air space is provided between this washer and the adjacent member and the washer is made thin 85 so that if the pressure is great the washer 90 will give to make a larger passageway.

Other features will be pointed out below.

In the drawings:

Figure 1 is a central vertical section of a fuse plug embodying our invention; 95

Fig. 2 is a section on line 2—2 of Fig. 1, looking in the direction of the arrows;

Fig. 3 is an elevation, partly in vertical section, of a modification;

Fig. 4 is a top plan of the inner washer;

Fig. 5 is a top plan of the outer washer;

Fig. 6 is a top plan of the intermediate washer;

Fig. 7 is a bottom plan of the same;

Fig. 8 is a perspective view of the upper 105 lining member;

Fig. 9 is a perspective view of the interposed member;

Fig. 10 is a perspective view of the lower lining member; and

Fig. 11 is a plan of the modified interposed member.

Shell A has an upper outturned flange a^1 , a threaded portion, an unthreaded pilot or lead portion a^2 of substantially less diameter than the threaded portion and an inturned flange a^3 , the latter having a central opening a^4 and openings a^5 in the form of perforations and other openings in the form of notches a^6 .

A tubular insulating lining of fiber is provided consisting of lower member B and upper member B^1 and held in place between these members is an interposed member B^2 having a passage or opening b^2 , this member B^2 acting as a partition extending across the interior of the plug and dividing the latter into two chambers, the opening b^2 providing an outlet for gases from each chamber to the other.

The fuse wire D is electrically connected at one end to the shell and at the other end is connected by solder d to center contact E, the fuse being bent as shown and passing through opening b^2 and in this way a substantial and positive barrier is formed against the holding of an arc, the member B^2 being a barrier interposed into the direct path extending from the point of connection of the fuse and shell to the point of connection of the fuse and center contact.

Fitting tightly within member B is fiber washer F having depressions f , each provided with a perforation f^1 forming a gas outlet, and having upwardly extending indentations f^2 and having a central aperture f^3 .

Intermediate fiber washer G is outside of, but adjacent to, the flange a^3 of the shell and has central aperture g , openings g^1 and upwardly extending indentations g^2 .

Outer fiber washer H has a central aperture h and upwardly extending indentations h^1 .

The three washers F, G and H are clamped together and to the flange a^3 of the shell by means of the head e and clenched portions e^1 e^2 of the center contact, the body of which passes through apertures f^3 , g and h . When so clamped the depressions f are in engagement with the notches a^6 to prevent relative rotation of the parts, indentations g^2 pass through openings a^4 and enter indentations f^2 thus further preventing relative rotation of the parts and indentations h^1 enter indentations g^2 from the bottom, thus further preventing relative rotation of the parts.

Washer H is relatively very thin and is preferably slightly spaced from washer G so that when gas escapes through perforations f^1 and openings g^1 it will escape be-

tween washers G and H, the latter regulating the flow of gas, it being clear that if the pressure is very great the washer H will yield sufficiently to allow proper vent. It will be observed that the lower face of depression f bears against the adjacent corner of opening g^1 and the more pressure of gas there is the tighter is the joint.

The outlet through perforation f^1 and opening g^1 is an insulated one which has the very important advantage of avoiding melting or burning metal parts and preventing flame outside the plug.

Exterior fiber insulation K is provided for a portion of the shell and is seated between flange a and ledge a^6 on the shell, this insulation having an extension k . A transparent cover L of mica rests on flange a . A metal ring M perforated at m and flanged at m^1 clamps the cover and extension k together and forms a hand hold, the extension k acting as insulation therefor.

In Fig. 3 we show another form of partition and barrier B^3 which has perforation b^3 and is elliptical in form and in this case the tubular lining B^4 is in one piece and this construction is desirable for some purposes.

Members B^2 and B^3 are close to the respective fuse wires D and D^1 and therefore furnish an excellent and convenient background so that the user can readily determine whether the fuse has blown or not. We prefer to have the members B^2 and B^3 of a color contrasting with the color of the fuse in order to increase the effectiveness of the background and we have found white fiber a very effective material of which members B^2 and B^3 may be made.

What we claim is:

1. In an electrical device the combination of a screw shell body member having an unthreaded lead portion on one end thereof; a center contact member, insulatively mounted on said end of the body member, said members to be electrically connected; a cover for the other end of said member; means to attach said cover; and an exterior insulation below said means.

2. In an electrical device the combination of a screw shell body member having an inturned flange on one end thereof with an unthreaded lead portion adjacent to said flange and extending part way up said shell; a plurality of insulating members held in adjacency to said flange; and a center contact attached to said end of the body member by said insulating members.

3. A fuse plug comprising a screw shell body member having an unthreaded lead portion; an insulating lining for said shell; a chamber in said body member; a center contact member; a fuse in said chamber connected to said members; insulation between said shell and center contact members; and means in said chamber interposed between said shell and center contact members; and means in said chamber interposed

- in the direct line between the points of connection of said fuse with said members; to intercept the direct path of an arc from one or said points to the other; an indirect 5 gas outlet from said chamber; a hand hold; and exterior insulation for a portion of said shell and exterior thereto and directly beneath the hand hold.
4. In an electrical device the combination 10 of a screw shell body member having an unthreaded lead portion on one end thereof; a metallic hand hold on the other end thereof; and means insulating said hand hold from said body and providing exterior insulation for a portion of said shell body member.
5. In an electrical device the combination 15 of a screw shell body member having a lead portion on one end thereof and a flange at the other end; an exterior insulation below said flange; a cap for said shell; a metallic hand and cap holding means, said means being insulated from said flange and shell by said exterior insulation.
- 20 6. A fuse plug comprising a screw shell body member; a tubular insulating lining for said member; a chamber within said lining; a cover for said chamber; metallic means to attach said cover, said means being insulated from the shell body member; a center contact member; an insulating support for attaching said contact member to said shell body member; a fuse connecting said members; and a separate member 25 within the body interposed in the direct line of connection of said fuse and said shell and center contact member.
7. A fuse plug comprising a screw shell body member; a tubular insulating lining 30 for said member; a center contact member; and an insulating support for attaching said center contact member to one end of said shell body member; a fuse connecting said members; means within the body member 35 interposed in the direct line between the points of connection of said fuse and said members to intercept the direct path of an arc from one of said points to the other; a cover for the other end of the plug; and metallic means insulated from the conduct- 40 ing members to connect said cover to said plug.
8. A fuse plug comprising a shell contact member; a center contact member; a chamber; a fuse in said chamber; and means interposed between the points of connection of said fuse to intercept the direct path of an arc from one of said points to the other; a gas outlet from said chamber; and means 45 to regulate said outlet for gases formed when said fuse blows.
9. In a fuse plug the combination of a plurality of contacts; an insulating chamber; a fuse in said chamber; and a gas outlet through one of the contacts, one of the 50
- walls of said chamber having a perforation corresponding with said outlet and forming an insulation for said outlet.
10. A fuse comprising a side contact; a center contact; a chamber; a fuse in said chamber; said fuse connecting said contacts; an outlet for gas through one of said contacts; and means to insulate said outlet.
11. A fuse plug comprising a shell contact; a center contact; a fuse; a chamber; and an outlet for gases through said shell contact and means to insulate said outlet and said shell and center contact.
12. In combination a shell with an in-turned flange provided with an opening; 80 a center contact; a washer insulating said shell and center contact and provided with a projection to engage said opening to prevent relative rotation of the shell and washer.
13. A fuse plug comprising a shell with an inturned flange provided with an opening; 85 a center contact; a washer insulating said shell and center contact and provided with a projection to engage said opening to prevent relative rotation of the shell and washer, said projection being provided with a gas outlet.
14. A fuse plug comprising a shell with an inturned flange provided with two openings; 90 a center contact; a washer inside the plug insulating said shell and center contact and provided with a projection to engage one of said openings to prevent relative rotation of the washer and shell, said projection being provided with a gas outlet; a second washer outside the shell and provided with a protuberance to engage the other of said openings in the shell and also provided with a perforation to receive the projection of the first washer.
15. A fuse plug comprising a side contact; a fuse chamber; a center contact at the bottom of said chamber; a fuse connecting said contacts; insulating material supporting said center contact; an outlet for gas through said insulating material; and a washer covering said outlet to receive the flash of an arc or hot gas blowing out through said outlet.
16. A fuse plug comprising a shell; a center contact; a fuse; a chamber; an insulating support for the center contact; said support having a gas outlet; a yieldable member on one side of said support and covering said outlet; said outlet to be regulated by the pressure of gas in said chamber acting upon said yieldable member when the fuse blows.
17. A fuse plug comprising a shell; a chamber; a fuse; a center contact; an insulating support for said contact; a gas outlet through said support; a yieldable member on one side of said support and covering said outlet; said outlet to be regulated

- 1 by the pressure of gas in said chamber acting upon the yieldable member on the blowing of said fuse; said support and member being provided with coöperating portions 5 to prevent relative rotation between them.
18. A fuse plug comprising a shell body member; a tubular lining therefor; a center contact; and insulation between said shell and contact comprising washers, one of 10 which fits within said tubular lining.
19. A fuse plug comprising a chamber; a fuse; a gas outlet; and means outside of 15 said chamber to regulate said outlet when the fuse blows.
20. A fuse plug comprising a shell; a center contact; insulation between said shell and contact and provided with a gas outlet; and means to regulate said outlet. 20
21. A fuse plug comprising a shell with an inturned flange provided with openings; a center contact; washers insulating said shell and contact and provided with projections to engage said openings to prevent 25 relative rotation between said washers and the shell and center contact, said washers being provided with a gas outlet; means to regulate said outlet; a fuse connected to the shell and center contact; a member interposed in the direct line between the points 30 of connection of the fuse with the shell and center contact; exterior insulation for said shell; and a hand hold.
22. A fuse plug comprising a screw shell body member; an insulating lining for said member; a center contact member; a fuse connecting said members; and a member separate from said lining to intercept the direct path of an arc from one of the points 35 of connection of said fuse to the other; a gas outlet; means to insulate said outlet; and means to regulate said outlet when the fuse blows.
23. A fuse plug comprising a screw shell body member; a center contact; a fuse; interior insulation; means to intercept the direct path of an arc caused by said fuse; a cover; means to attach said cover, said means being insulated from the conducting member; exterior insulation for said body 45 member; a gas outlet from said body member; and means to regulate said outlet for gases formed when said fuse blows.
24. A fuse plug comprising a shell; an insulating lining therefor comprising two 50 pieces; and a member extending crosswise of the plug and held in place by said two pieces.
25. A fuse plug comprising a screw shell body member; tubular lining therefor; a center contact at one end of said member; a closure for that end of the plug; a cover for the other end of the said plug and forming a chamber; a member extending crosswise of the chamber and dividing the interior thereof into two sections; a fuse 55 con-
- nected to said shell; exterior insulation for said shell; means to attach a metallic band and cover holding means, said metallic means being insulated from the conducting members.
26. A fuse plug comprising a shell contact; a chamber; a center contact; a fuse; a gas outlet at the center contact end of the plug; and means to regulate the flow of gas through said outlet, said means being regulated by the pressure of gas within said chamber when the fuse blows. 70
27. A fuse plug comprising a shell; a center contact; and a plurality of washers to insulate the shell and center contact, said washers having portions coöperating to prevent relative rotation between them. 75
28. A fuse plug comprising a shell; a center contact; a chamber; a fuse in said chamber; a washer insulating the shell from the center contact and provided with a gas outlet; and a member to regulate said outlet, said outlet being regulated by gas pressure from within said chamber when the fuse blows and said washer and said member 80 having portions coöperating to prevent relative rotation between them. 90
29. In a fuse the combination of a plurality of contacts; a chamber; a fuse in said chamber; an outlet for gas through one of 95 said contacts; means to insulate said outlet; and means to regulate said outlet when the fuse blows.
30. In a fuse the combination of a plurality of contacts; a chamber; a fuse in said chamber; an outlet for gas from said chamber; and means outside of said chamber to regulate said outlet. 100
31. A fuse plug comprising a side contact; a fixed center contact, a chamber; a fuse in said chamber; a gas outlet from said chamber; and means to regulate said outlet, said means being regulated by the pressure of gases within said chamber when a fuse 105 blows.
32. In a fuse the combination of a plurality of contacts; a chamber; a fuse in said chamber; a gas outlet from said chamber, and means located outside said chamber and acting by gas pressure when a fuse blows to 115 regulate said outlet.
33. In a fuse the combination of a chamber; a plurality of fixed contacts; a fuse electrically connected to said contacts; a gas outlet; and means to regulate said outlet. 120
34. In a fuse the combination of a plurality of contacts; a chamber; a fuse in said chamber and directly connected with said contacts; a gas outlet from said chamber; and means to regulate said outlet, said means being controlled by the gas pressure in said chamber when a fuse blows. 125
35. In a fuse the combination of a plurality of contacts; a chamber; a fuse in said chamber; a gas outlet from said chamber; 130

and means independent of said contacts to regulate said outlet.

36. An insulating lining for a fuse plug having a screw shell body member, said lining comprising a partition piece with a fuse passage therein and tubular portions extending each side of said partition piece.

37. A fuse plug comprising two fixed con-

tacts, each having a portion exposed externally of the device; a chamber; a fuse in said chamber connecting said fixed contacts; a gas outlet from said chamber; and means to regulate said outlet when the fuse blows.
